NURSING BOTTLE HOLDER

Robert M. Dean, Auburn, N. Y.

Application December 21, 1948, Serial No. 66,485

1 Claim. (Cl. 248—104)

1 The present invention relates to a nursing bottle holder so constructed and fashioned that it lends itself to appropriate holding and effective maintenance of marketed types of nursing bottles and functions in a manner to permit a bottle to be suspended in an inverted position from the back of a high-chair, side of a crib, bassinette or play-pen where, same will be convenient and available to a baby occupant whether reclining or sitting.

It is a matter of common knowledge to those skilled in the art to which the invention relates that many and varied forms and styles of bottle holders have been devised and used with varying degrees of success and unqualified approval. Generally visualized bottle holders which have come to my attention usually embody some sort of clamp or equivalent fitting for attachment to the crib or other furniture, a holder to embrace the bottle per se, and various styles and forms of brackets, fixtures and devices for joining the holder with the furniture clamp. As a matter of fact the broad description just mentioned generically comprehends the invention herein shown and described. However, in reducing to practice a preferred and specific embodiment of a structure embodying all requisite needs I have evolved and produced a bottle holder which is formed from a single piece of wire which is twisted and bent in diverse ways to provide reliable and aptly designed facilities for supporting and positioning the bottle with requisite nicety that it may be advantageously used by an infant incapable of holding and conveniently manipulating its bottle.

In reducing to practice a preferred embodiment of my invention I provide a nursing bottle suspending and holding device which, as stated, is fashioned from twistable and bendable wire and which is characterized by a readily bendable reach and holder suspending arm, the latter being tractable in nature so that it may be shaped by hand to suit a given occasion after which it will stay put, due to malleable properties, to situate and maintain the bottle where wanted.

Other objects and advantages, more specific and structural in character, will become more readily apparent from the following description and the accompanying and illustrative drawings.

In the drawings:

Figure 1 is a perspective view of a nursing bottle support and holder constructed in accordance with the invention showing the manner in which same is attached to a wall or side of a crib and the manner in which the bottle is vertically held

2 in an inverted position that the user may have access to same.

Figure 2 is a view on a smaller scale and in elevation, thrown somewhat into perspective, and showing how the bottle may be tiltably held to be conveniently employed when the baby is sitting, let us say, in a high-chair.

Briefly summarized, my invention has to do with a nursing bottle holder which is fashioned

10 from a single length of malleable wire the latter formed into a bendable hand-set elongated reach arm provided at one end with clamping and retaining jaws applicable to a relatively fixed support, said arm being formed at its opposite end 15 into a single strand, the latter being disposed laterally to said arm and being bent upon itself into a finger-loop and then bent adjacent to said loop into opposed semicircular bends, the latter being diametrically opposite and in a plane with each 20 other, as well as in a plane with said finger-loop and collectively defining a closed bottle embracing ring, the end portion of said strand being then directed at right angles to said ring, at a point diametrically opposite to said finger-loop, 25 and defining a brace, the free end of the latter being laterally directed and formed into a split ring in spaced parallelism with said first first named ring, and the terminal of said strand being finally formed into a latching hook, the latter 30 being in a plane with the split ring and at right angles to said brace.

Referring now to the drawings by distinguishing reference characters it will be seen that the clamping and attaching means is denoted by the 35 numeral 5, that the reach limb or arm is denoted by the numeral 6 and the holder for the bottle B is denoted at 7. These are the three essential components of the overall structure. As stated the latter is fashioned from wire of desired 40 pliancy which length of wire is bent between its ends and the portions twisted to provide the twisted arm portion or limb 6 and the jaw-like grips 8 and 9. These are suitably portioned and shaped to engage over the wall of a crib 10, or

45 any other suitable support such as a high-chair or the like (not shown). The numeral 11 designates a rubber or equivalent ferrule which is arranged to provide a collar and to cover the raw wire-ends (not shown). We observe the ferrule 50 11 at the point of juncture of the clamping means 5 and limb or arm 6. There is a similar sleeve or ferrule 12 at the opposite end of the arm and this is situated at the point where the free single strand of the wire takes a bend at 13 and is then 55 fashioned into an auxiliary reach 14 formed into

a semi-circular bend at 15, twisted at 16, bent into an eye at 17 and again twisted into a second semi-circular bend as at 18. The two portions bends 15 and 18 provide a satisfactory bottle ring or grip for the neck portion of the bottle. The wire-end then takes a bend 19 at right angles to the neck ring and is then formulated into a split ring 20 for embracing the basal end of the bottle and finally the free terminal portion is fashioned into a hook at 21 which is releasably engageable with the bendable reach arm 6. The reader will observe a space at 22 which makes the split ring expandable and contractable and aptly suited to accommodate bottles of different sizes. In Figure 1 we see the bottle in a vertical position which is the position normally assumed when the device is used on a crib as illustrated in said Figure 1. In Figure 2 we are to assume that the device is being used on the high-chair and that the bottle holder is then angled to an approximately "down" and "in" slanting position where, the nipple is rendered ready and handy for a tot sitting in a high-chair. The bend 13 is made to permit this shifting of the bottle holder 7 to the position shown in Figure 2 at which time the hook 21 is released from the reach arm. As stated, the reach arm is sufficiently malleable as to allow it to be curved and bent and positioned where necessary and to stay put once it is set for use.

When the clamp including the jaws 8 and 9 is in use a diaper or other convenient piece of cloth (not shown) may be folded and employed as a protector pad to keep the gripping jaws from scarring or marring the furniture surfaces. When the clamp is pushed down over the back of a chair or side rail of some piece of baby furniture said clamp affords a grip which is sufficient in strength to keep the entire holder in proper position. In actual use the suspending arm is approximately semi-circular and arches over the baby's head from the clamp to the bottle holder. The arm may be bent to put the bottle in proper position as the baby progresses from a reclining position to a sitting position and may be bent into a small complete circle for ease in carrying in a diaper bag or similar container. The design of the baby bottle holder makes it suitable for all popular types of nursing bottles. The holder, may be washed, boiled or disinfected in a convenient way without being damaged. The loop 17 serves not only as a finger grip but may be employed for suspending small toys, teething rings and other objects of attraction for use by babies.

Novelty is predicated upon a simple and economical bottle holder which is wrought from wire with the major portions twisted to provide double jaw clamping and attaching means at one end of an elongated reach arm, said reach arm being yieldable and tractable in character that it may be shaped up and located according to the varying requirements. The malleable characteristic whereby the arm stays substantially put, once it is bent to form and positioned is important. The fashioning of the single strand of the free end 65

portion into a novel bottle holder is likewise important and in connection with the bottle holder I stress the upper and lower rings connected by a brace with a lower ring bendably connected to the arm for changing the angularity of the ring and bottle, plus the latching hook forming a significant feature of the split ring at the top which permits the bottle to be either latched in place, as shown in Figure 1, or unlatched and swung to the oblique angled position shown in Figure 2.

A careful consideration of the foregoing description in conjunction with the invention as illustrated in the drawings will enable the reader to obtain a clear understanding and impression 15 of the alleged features of merit and novelty sufficient to clarify the construction of the invention as hereinafter claimed.

Minor changes in shape, size, materials and rearrangement of parts may be resorted to in actual practice so long as no departure is made 20 from the invention as claimed.

Having described the invention, what is claimed as new is:

A nursing bottle holder fashioned from a single 25 length of malleable wire, the latter formed into a bendable hand-set elongated reach arm provided at one end with clamping and retaining jaws applicable to a relatively fixed support, said arm being formed at its opposite end into a single 30 strand, the latter being disposed laterally to said arm and being bent upon itself into a finger-loop and then bent adjacent to said loop into opposed semi-circular bends, the latter being diametrically opposite and in a plane with each other, as well 35 as in a plane with said finger-loop and collectively defining a closed bottle embracing ring, the end portion of said strand being then directed at right angles to said ring, at a point diametrically opposite to said finger-loop, and defining a brace, 40 the free end of the latter being laterally directed and formed into a split ring in spaced parallelism with said first named ring, and the terminal of said strand being finally formed into a latching hook to engage the arm, the latter being in a 45 plane with the split ring and at right angles to said brace.
